(57) **ABSTRACT**

A bed frame has left, intermediate and right longitudinal support bars, each having two main body sections and an intermediate section connected between two main body sections, via a connecting piece. A first through hole is disposed at an end of each of the main body sections adjacent to the intermediate section. The connecting piece is provided with a second through hole on a side connected to the main body section. When the second through hole is aligned with the first through hole, a support bar pivot shaft can run through the first through hole and second through

(Continued)

hole so that the two main body sections can rotate about their respective support bar pivot shafts in a vertical plane relative to the intermediate section. Folding the bed frame is simple and easy to implement, and the bed frame, in a folded state, facilitates transportation and compact storage.

BED FRAME

**CROSS-REFERENCE TO RELATED
APPLICATIONS**

This application claims the benefit of Chinese Patent Application No. 201910750474.0, filed Aug. 14, 2019, which is incorporated herein by reference in its entirety.

FIELD OF THE DISCLOSURE

The present disclosure relates to the field of furniture, and specifically to a bed frame.

BACKGROUND OF THE DISCLOSURE

Foldable beds have become popular furniture products. However, the folding function of the existing foldable beds is usually not ideal, and they may lack sufficient rigidity and stability. Further, since existing bed frames are sold as a whole after the completion of assembly at the factory, consumers can use and store the bed frames only by folding and unfolding the bed frames, but cannot detach or disassemble elements of the bed frame. Thus, existing folding bed frames tend to be bulky, requiring excessive storage space and transportation costs.

Accordingly, improved folding bed frames are needed.

SUMMARY OF THE DISCLOSURE

A main object of the present disclosure is to provide a bed frame enabling a user to quickly and effectively fold the bed frame. The space occupied by the folded bed frame is small. The folding process is relatively simple and easy to implement, the bed frame exhibits larger strength and better 35 stability and can satisfy the user's many demands.

An aspect of the present disclosure provides a bed frame, comprising:

a left longitudinal support bar and a right longitudinal support bar which are located at a left side and a right side of the bed frame respectively and extend in a longitudinal direction of the bed frame;

an intermediate longitudinal support bar disposed between the left longitudinal support bar and the right longitudinal support bar and extending in the longitudinal direction of the bed frame,

the left longitudinal support bar, the right longitudinal support bar and the intermediate longitudinal support bar respectively comprise two main body sections and an intermediate section connected between the two main body sections, the main body sections and the intermediate section being connected together via a connecting sheet,

wherein a first through hole extending and running through transversely is disposed at an end of each of the main body sections adjacent to the intermediate section, the connecting sheet is provided with a second through hole on a side connected to the main body section; when the second through hole is aligned with the first through hole, a support bar pivot shaft can run through the first through hole and second through hole so that the two main body sections can rotate about their respective support bar pivot shafts in a vertical plane relative to the intermediate section, so that the bed frame is folded or unfolded in the vertical plane.

According to a further embodiment of the invention, the bed frame further comprises a locking mechanism for lock-

2

ing the main body sections relative to the intermediate section when the main body sections rotate to the folded or unfolded position in the vertical plane.

According to a further embodiment of the invention, the bed frame further comprises four connecting rods comprising two left connecting rods extending between the left longitudinal support bar and the intermediate longitudinal support bar and two right connecting rods extending between the right longitudinal support bar and the intermediate longitudinal support bar,

wherein each of the connecting rods comprises a plurality of bushings which are nested one inside another so that the connecting rods are telescopic in its extension direction.

According to a further embodiment of the invention, in any two adjacent bushings, one bushing is provided with a first alignment hole, a ball end leaf spring with a protrusion is disposed in the first alignment hole, the ball end leaf spring is configured to extend out of the first alignment hole under action of an elastic force and retract back into the first alignment hole when subjected to a pressure, the other the bushing is nested around a preceding the bushing, a second alignment hole is disposed on a side face of the other bushing opposite to the first alignment hole, the second alignment hole is configured in a way that when the second alignment hole aligns with the protrusion, the protrusion can extend out under the action of elasticity, automatically enter the second alignment hole and thereby lock the two adjacent bushings relative to one another.

According to a further embodiment of the invention, the bed frame further comprises:

two spaced-apart sliding sleeves disposed on the intermediate longitudinal support bar and being slidable on the intermediate longitudinal support bar, wherein a bracket is disposed on the sliding sleeve; and

four connecting rods comprising two left connecting rods extending between the left longitudinal support bar and the intermediate longitudinal support bar and two right connecting rods extending between the right longitudinal support bar and the intermediate longitudinal support bar, wherein one end of each of the connecting rods is pivotally attached to an end of the left longitudinal support bar or the right longitudinal support bar about a pivot shaft, and the other end of the connecting rod is pivotally attached to the corresponding bracket, wherein the connecting rod is configured in a way that the end of the connecting rod mounted on the bracket moves along with the sliding sleeve when the sliding sleeve slides along the intermediate longitudinal support bar, thereby driving the connecting rod to move on a horizontal plane such that the bed frame is in an unfolded state or a folded state.

According to a further embodiment of the invention, when the sliding sleeves slide toward each other along the intermediate longitudinal support bar, the bed frame is gradually folded until the bed frame gets into the folded state in which the left longitudinal support bar, the right longitudinal support bar, the intermediate longitudinal support bar and the connecting rods abut against one another; when the sliding sleeves slide away from each other along the intermediate longitudinal support bar, the bed frame is gradually unfolded until the bed frame gets into a state in which the respective connecting rods are perpendicular to the left longitudinal support bar, the right longitudinal support bar and the intermediate longitudinal support bar, respectively.

According to a further embodiment of the invention, the intermediate longitudinal support bar is provided with a pin

hole at positions close to its end portions and middle portion respectively, a pin is disposed in the pin hole, and the pin is configured to extend out of the pin hole under the action of an elastic force and retract back into the pin hole when subjected to pressure.

According to a further embodiment of the invention, a receiving hole is disposed on a side of the sliding sleeve opposite to the pin hole, wherein the receiving hole is configured in a way that when the receiving hole is aligned with the pin, the pin can extend out under the action of its elasticity, and automatically enter the receiving hole to lock the sliding sleeve on the intermediate longitudinal support bar.

According to a further embodiment of the invention, the pin holes at the end portions of the intermediate longitudinal support bar are positioned in a way that the connecting rods are perpendicular to the intermediate longitudinal support bar when the connecting rods are locked on the intermediate longitudinal support bar; the pin hole at the middle portion of the intermediate longitudinal support rod is positioned in a way that when the connecting rods are locked, the connecting rods and the intermediate longitudinal support bar abut against one another side by side.

According to a further embodiment of the invention, the pin is a square pin or a round pin.

According to a further embodiment of the invention, the pin holes are provided on an upper surface and/or a lower surface of the intermediate longitudinal support bar.

According to a further embodiment of the invention, the bracket is mounted on the sliding sleeve, and the bracket is provided with a pivot shaft located on both lateral sides of the sliding sleeve and extending in a vertical direction, and the connecting rod is pivotally connected to the bracket via the pivot shaft.

According to a further embodiment of the invention, the bracket comprises an upper plate mounted on an upwardly facing surface of the sliding sleeve and a lower plate fixedly mounted on a downwardly facing surface of the sliding sleeve, both lateral sides of the upper plate and lower plate respectively extend out of the sliding sleeve to form cantilevers, and the pivot shafts are connected between the cantilevers on the same side of the upper plate and lower plate.

According to a further embodiment of the invention, the upper plate comprises two horizontal engagement plates which are respectively connected to two pivot shafts located on both lateral sides of the sliding sleeve, the engagement plates are in a sector shape and provided with a gear structure on an arcuate edge thereof, the gear structures of the two upper plates connected to one sliding sleeve face each other and can mesh with each other, thereby enabling synchronous rotation of the two connecting rods connected to the sliding sleeve.

According to a further embodiment of the invention, an end of the connecting rod connected to the sliding sleeve has an upper side plate and a lower side plate which extend in the horizontal direction and face each other, and the pivot shaft is located between the upper side plate and the lower side plate,

and, the bracket includes a bearing frame and a retaining plate, the bearing frame is fixedly mounted on a lower side of the sliding sleeve and extending laterally relative to the sliding sleeve to be supported below the lower side plate, and the retaining plate is positioned above the lower side plate to achieve limitation of the end of the connecting rod connected to the sliding sleeve in the vertical direction.

According to a further embodiment of the invention, the upper side plate is formed as a partially circular shape, an edge of the circular shape is formed as a gear structure, a rack extending in the longitudinal direction is disposed on both lateral upper edges of the sliding sleeve respectively, the gear structures of two connecting rods connected to one sliding sleeve can respectively mesh with respective racks so that the two connecting rods connected to the sliding sleeve can rotate synchronously.

According to a further embodiment of the invention, the left longitudinal support bar, the right longitudinal support bar and the intermediate longitudinal support bar respectively comprise two main body sections and an intermediate section connected between the two main body sections, the main body sections and the intermediate section are connected via a connecting sheet, a support bar pivot shaft is mounted on the connecting sheet, the two main body sections are configured to be capable of rotating relative to each other about their respective support bar pivot shafts in a vertical plane relative to the intermediate section so that the bed frame is folded or unfolded in the vertical plane.

According to a further embodiment of the invention, the bed frame further comprises a locking mechanism for locking the main body sections relative to the intermediate section when the main body sections rotate to the folded or unfolded position in the vertical plane.

According to a further embodiment of the invention, the connecting rod comprises a plurality of bushings which are nested one inside another so that the connecting rod is telescopic in its extension direction.

According to a further embodiment of the invention, in any two adjacent bushings, one bushing is provided with a first alignment hole, a ball end leaf spring with a protrusion is disposed in the first alignment hole, the ball end leaf spring is configured to extend out of the first alignment hole under action of an elastic force and retract back into the first alignment hole when subjected to a pressure, the other the bushing is nested around a preceding bushing, a second alignment hole is disposed on a side face of the other bushing opposite to the first alignment hole, the second alignment hole is configured in a way that when the second alignment hole aligns with the protrusion, the protrusion can extend out under the action of elasticity, automatically enter the second alignment hole and thereby lock the two adjacent bushings relative to one another.

According to a further embodiment of the invention, the bed frame is configured to be engageable with a tongue member for mounting a headboard or bedhead member, the tongue member comprises a tongue, an upwardly open slot is provided at the end of the left longitudinal support bar and right longitudinal support bar, and the slot is configured to receive the tongue.

According to a further embodiment of the invention, the left longitudinal support bar, the right longitudinal support bar, and the intermediate longitudinal support bar are respectively provided with downwardly extending legs at both ends and in the middle.

In one embodiment, the legs are also pivotally connected to respective longitudinal support bars, the legs are rotatable and foldable relative to the respective longitudinal support bars, and in the folded state the legs abut against the respective longitudinal support bars side by side.

Another aspect of the present disclosure provides a bed frame, comprising:

a left longitudinal support bar and a right longitudinal support bar which are located on both lateral sides of

the bed frame respectively and extend in a longitudinal direction of the bed frame; an intermediate longitudinal support bar disposed between the left longitudinal support bar and the right longitudinal support bar and extending in the longitudinal direction of the bed frame, wherein the bed frame further comprises: four sliding sleeves, wherein two sliding sleeves are disposed spaced apart on the left longitudinal support bar and capable of sliding on the left longitudinal support bar, and the remaining two sliding sleeves are disposed spaced apart on the right longitudinal support bar and capable of sliding on the right longitudinal support bar, wherein a bracket is disposed on the sliding sleeve; and four connecting rods comprising two left connecting rods extending between the left longitudinal support bar and the intermediate longitudinal support bar and two right connecting rods extending between the right longitudinal support bar and the intermediate longitudinal support bar, wherein one end of each of the connecting rods is pivotally attached to an end of the intermediate longitudinal support bar about a pivot shaft, and the other end of the connecting rod is pivotally attached to the corresponding bracket, wherein the connecting rod is configured in a way that the end of the connecting rod mounted on the bracket moves along with the sliding sleeve when the sliding sleeve slides along the left longitudinal support bar or right longitudinal support bar, thereby driving the connecting rod to move on a horizontal plane such that the bed frame is in an unfolded state or a folded state.

According to a further embodiment of the invention, when the sliding sleeves slide toward each other along the left longitudinal support bar or right longitudinal support bar, the bed frame is gradually folded until the bed frame gets into the folded state in which the left longitudinal support bar, the right longitudinal support bar, the intermediate longitudinal support bar and the connecting rods abut against one another; when the sliding sleeves slide away from each other along the left longitudinal support bar or right longitudinal support bar, the bed frame is gradually unfolded until the bed frame gets into a state in which the respective connecting rods are perpendicular to the left longitudinal support bar, the right longitudinal support bar and the intermediate longitudinal support bar, respectively.

According to a further embodiment of the invention, a pin hole is disposed on the left longitudinal support bar or right longitudinal support bar at positions close to its end portions and middle portion and at a transition position between the end portions and the middle portion, respectively, a pin is disposed in the pin hole, and the pin is configured to extend out of the pin holes under the action of an elastic force and retract back into the pin holes when subjected to pressure.

According to a further embodiment of the invention, a receiving hole is disposed on a side of the sliding sleeve opposite to the pin hole, wherein the receiving hole is configured in a way that when the receiving hole is aligned with the pin, the pin can extend out under the action of its elasticity, and automatically enter the receiving hole to lock the sliding sleeve on the corresponding left longitudinal support bar or right longitudinal support bar.

According to a further embodiment of the invention, the pin holes at the end portions of the left longitudinal support bar or right longitudinal support bar are positioned in a way that the connecting rods are perpendicular to the intermediate longitudinal support bar when the connecting rods are

locked on the left longitudinal support bar or right longitudinal support bar; the pin hole at the middle portion of left longitudinal support bar or right longitudinal support bar is positioned in a way that when the connecting rods are locked, the connecting rods and the intermediate longitudinal support bar abut against one another side by side; the pin hole at a transition position of left longitudinal support bar or right longitudinal support bar is positioned in a way that when the connecting rods are locked, an angle between the connecting rods and the intermediate longitudinal support bar is an acute angle.

According to a further embodiment of the invention, the pin is a square pin or a round pin.

According to a further embodiment of the invention, the pin holes are provided on an upper surface and/or a lower surface of the left longitudinal support bar or the right longitudinal support bar.

According to a further embodiment of the invention, the bracket is mounted on the sliding sleeve, and the bracket is provided with a pivot shaft located on both lateral sides of the sliding sleeve and extending in a vertical direction, and the connecting rod is pivotally connected to the bracket via the pivot shaft.

According to a further embodiment of the invention, the bracket comprises an upper plate mounted on an upwardly facing surface of the sliding sleeve and a lower plate fixedly mounted on a downwardly facing surface of the sliding sleeve, both lateral sides of the upper plate and lower plate respectively extend out of the sliding sleeve to form cantilevers, and the pivot shafts are connected between the cantilevers on the same side of the upper plate and lower plate.

According to a further embodiment of the invention, the upper plate comprises two horizontal engagement plates which are respectively connected to two pivot shafts located on both lateral sides of the sliding sleeve, the engagement plates are in a sector shape and provided with a gear structure on an arcuate edge thereof, the gear structures of the two upper plates connected to one sliding sleeve face each other and can mesh with each other, thereby enabling synchronous rotation of the two connecting rods connected to the sliding sleeve.

According to a further embodiment of the invention, an end of the connecting rod connected to the sliding sleeve has an upper side plate and a lower side plate which extend in the horizontal direction and face each other, and the pivot shaft is located between the upper side plate and the lower side plate, and

the bracket includes a bearing frame and a retaining plate, the bearing frame is fixedly mounted on a lower side of the sliding sleeve and extending laterally relative to the sliding sleeve to be supported below the lower side plate, and the retaining plate is positioned above the lower side plate to achieve limitation of the end of the connecting rod connected to the sliding sleeve in the vertical direction.

According to a further embodiment of the invention, the upper side plate is formed as a partially circular shape, an edge of the circular shape is formed as a gear structure, a rack extending in the longitudinal direction is disposed on both lateral upper edges of the sliding sleeve respectively, the gear structures of two connecting rods connected to one sliding sleeve can respectively mesh with respective racks so that the two connecting rods connected to the sliding sleeve can rotate synchronously.

According to a further embodiment of the invention, the left longitudinal support bar, the right longitudinal support

bar and the intermediate longitudinal support bar respectively comprise two main body sections and an intermediate section connected between the two main body sections, the main body sections and the intermediate section are connected via a connecting sheet, a support bar pivot shaft is mounted on the connecting sheet, the two main body sections are configured to be capable of rotating relative to each other about their respective support bar pivot shafts in a vertical plane relative to the intermediate section so that the bed frame is folded or unfolded in the vertical plane.

According to a further embodiment of the invention, the bed frame further comprises a locking mechanism for locking the main body sections relative to the intermediate section when the main body sections rotate to the folded or unfolded position in the vertical plane.

According to a further embodiment of the invention, the connecting rod comprises a plurality of bushings which are nested one inside another so that the connecting rod is telescopic in its extension direction.

According to a further embodiment of the invention, in any two adjacent bushings, one bushing is provided with a first alignment hole, a ball end leaf spring with a protrusion is disposed in the first alignment hole, the ball end leaf spring is configured to extend out of the first alignment hole under action of an elastic force and retract back into the first alignment hole when subjected to a pressure, the other the bushing is nested around a preceding the bushing, a second alignment hole is disposed on a side face of the other bushing opposite to the first alignment hole, the second alignment hole is configured in a way that when the second alignment hole aligns with the protrusion, the protrusion can extend out under the action of elasticity, automatically enter the second alignment hole and thereby lock the two adjacent bushings relative to one another.

According to a further embodiment of the invention, the bed frame is configured to be engageable with a tongue member for mounting a headboard, the tongue member comprises a tongue, an upwardly open slot is provided at the end of the left longitudinal support bar and right longitudinal support bar, and the slot is configured to receive the tongue.

According to a further embodiment of the invention, the left longitudinal support bar, the right longitudinal support bar, and the intermediate longitudinal support bar are respectively provided with downwardly extending legs at both ends and in the middle.

In one embodiment, the legs are also pivotally connected to respective longitudinal support bars, the legs are rotatable and foldable relative to the respective longitudinal support bars, and in the folded state the legs abut against the respective longitudinal support bars side by side.

A further aspect of the present disclosure provides a bed frame, comprising:

- a left longitudinal support bar and a right longitudinal support bar which are located on both lateral sides of the bed frame respectively and extend in a longitudinal direction of the bed frame;
- an intermediate longitudinal support bar disposed between the left longitudinal support bar and the right longitudinal support bar and extending in the longitudinal direction of the bed frame;
- two spaced-apart sliding sleeves disposed on the intermediate longitudinal support bar and being slidable on the intermediate longitudinal support bar, wherein a bracket is disposed on the sliding sleeve; and
- four connecting rods comprising two left connecting rods extending between the left longitudinal support bar and the intermediate longitudinal support bar and two right

connecting rods extending between the right longitudinal support bar and the intermediate longitudinal support bar, wherein one end of each of the connecting rods is pivotally attached to an end of the left longitudinal support bar or the right longitudinal support bar about a pivot shaft, and the other end of the connecting rod is pivotally attached to the corresponding bracket, wherein the connecting rod is configured in a way that the end of the connecting rod mounted on the bracket moves along with the sliding sleeve when the sliding sleeve slides along the intermediate longitudinal support bar, thereby driving the connecting rod to move on a horizontal plane such that the bed frame is in an unfolded state or a folded state; and

wherein the bed frame further comprises at least two additional links extending between the intermediate longitudinal support bar and the connecting rods, one end of each of the additional links is pivotally connected to one end of the intermediate longitudinal support bar, the other end is pivotally connected to the connecting rod, and when the connecting rod moves in a horizontal plane, the additional link can be driven by the connecting rod to move in a horizontal plane.

According to a further embodiment of the invention, the additional links comprise two additional links, and the two additional links are located on the same side relative to the intermediate longitudinal support bar; or

the additional links comprise two additional links, and the two additional links are located on different sides relative to the intermediate longitudinal support bar.

According to a further embodiment of the invention, the additional links comprise two additional links, and the two additional links are located on different sides relative to the intermediate longitudinal support bar, and one ends of the two additional links are respectively connected to opposing ends of the intermediate longitudinal support bar.

According to a further embodiment of the invention, the additional links comprise four additional links

According to a further embodiment of the invention, when the sliding sleeves slide toward each other along the intermediate longitudinal support bar, the bed frame is gradually folded until the bed frame gets into the folded state in which the left longitudinal support bar, the right longitudinal support bar, the intermediate longitudinal support bar and the connecting rods abut against one another; when the sliding sleeves slide away from each other along the intermediate longitudinal support bar, the bed frame is gradually unfolded until the bed frame gets into a state in which the respective connecting rods are perpendicular to the left longitudinal support bar, the right longitudinal support bar and the intermediate longitudinal support bar, respectively.

According to a further embodiment of the invention, the intermediate longitudinal support bar is provided with a pin hole at positions close to its end portions and middle portion respectively, a pin is disposed in the pin hole, and the pin is configured to extend out of the pin hole under the action of an elastic force and retract back into the pin hole when subjected to pressure.

According to a further embodiment of the invention, a receiving hole is disposed on a side of the sliding sleeve opposite to the pin hole, wherein the receiving hole is configured in a way that when the receiving hole is aligned with the pin, the pin can extend out under the action of its elasticity, and automatically enter the receiving hole to lock the sliding sleeve on the intermediate longitudinal support bar.

According to a further embodiment of the invention, the pin holes at the end portions of the intermediate longitudinal support bar are positioned in a way that the connecting rods are perpendicular to the intermediate longitudinal support bar when the connecting rods are locked on the intermediate longitudinal support bar; the pin hole at the middle portion of the intermediate longitudinal support rod is positioned in a way that when the connecting rods are locked, the connecting rods and the intermediate longitudinal support bar abut against one another side by side.

According to a further embodiment of the invention, the pin is a square pin or a round pin.

According to a further embodiment of the invention, the pin holes are provided on an upper surface and/or a lower surface of the intermediate longitudinal support bar.

According to a further embodiment of the invention, the bracket is mounted on the sliding sleeve, and the bracket is provided with a pivot shaft located on both lateral sides of the sliding sleeve and extending in a vertical direction, and the connecting rod is pivotally connected to the bracket via the pivot shaft.

According to a further embodiment of the invention, the bracket comprises an upper plate mounted on an upwardly facing surface of the sliding sleeve and a lower plate fixedly mounted on a downwardly facing surface of the sliding sleeve, both lateral sides of the upper plate and lower plate respectively extend out of the sliding sleeve to form cantilevers, and the pivot shafts are connected between the cantilevers on the same side of the upper plate and lower plate.

According to a further embodiment of the invention, the upper plate comprises two horizontal engagement plates which are respectively connected to two pivot shafts located on both lateral sides of the sliding sleeve, the engagement plates are in a sector shape and provided with a gear structure on an arcuate edge thereof, the gear structures of the two upper plates connected to one sliding sleeve face each other and can mesh with each other, thereby enabling synchronous rotation of the two connecting rods connected to the sliding sleeve.

According to a further embodiment of the invention, an end of the connecting rod connected to the sliding sleeve has an upper side plate and a lower side plate which extend in the horizontal direction and face each other, and the pivot shaft is located between the upper side plate and the lower side plate, and

the bracket includes a bearing frame and a retaining plate, the bearing frame is fixedly mounted on a lower side of the sliding sleeve and extending laterally relative to the sliding sleeve to be supported below the lower side plate, and the retaining plate is positioned above the lower side plate to achieve limitation of the end of the connecting rod connected to the sliding sleeve in the vertical direction.

According to a further embodiment of the invention, the upper side plate is formed as a partially circular shape, an edge of the circular shape is formed as a gear structure, a rack extending in the longitudinal direction is disposed on both lateral upper edges of the sliding sleeve respectively, the gear structures of two connecting rods connected to one sliding sleeve can respectively mesh with respective racks so that the two connecting rods connected to the sliding sleeve can rotate synchronously.

According to a further embodiment of the invention, the left longitudinal support bar, the right longitudinal support bar and the intermediate longitudinal support bar respectively comprise two main body sections and an intermediate section connected between the two main body sections, the

main body sections and the intermediate section are connected via a connecting sheet, a support bar pivot shaft is mounted on the connecting sheet, the two main body sections are configured to be capable of rotating relative to each other about their respective support bar pivot shafts in a vertical plane relative to the intermediate section so that the bed frame is folded or unfolded in the vertical plane.

According to a further embodiment of the invention, the bed frame further comprises a locking mechanism for locking the main body sections relative to the intermediate section when the main body sections rotate to the folded or unfolded position in the vertical plane.

According to a further embodiment of the invention, the connecting rod comprises a plurality of bushings which are nested one inside another so that the connecting rod is telescopic in its extension direction.

According to a further embodiment of the invention, in any two adjacent bushings, one bushing is provided with a first alignment hole, a ball end leaf spring with a protrusion is disposed in the first alignment hole, the ball end leaf spring is configured to extend out of the first alignment hole under action of an elastic force and retract back into the first alignment hole when subjected to a pressure, the other the bushing is nested around a preceding the bushing, a second alignment hole is disposed on a side face of the other bushing opposite to the first alignment hole, the second alignment hole is configured in a way that when the second alignment hole aligns with the protrusion, the protrusion can extend out under the action of elasticity, automatically enter the second alignment hole and thereby lock the two adjacent bushings relative to one another.

According to a further embodiment of the invention, the bed frame is configured to be engageable with a tongue member for mounting a headboard, the tongue member comprises a tongue, an upwardly open slot is provided at the end of the left longitudinal support bar and right longitudinal support bar, and the slot is configured to receive the tongue.

According to a further embodiment of the invention, the left longitudinal support bar, the right longitudinal support bar, and the intermediate longitudinal support bar are respectively provided with downwardly extending legs at both ends and in the middle.

In one embodiment, the legs are also pivotally connected to respective longitudinal support bars, the legs are rotatable and foldable relative to the respective longitudinal support bars, and in the folded state the legs abut against the respective longitudinal support bars side by side.

A further aspect of the present disclosure provides a bed frame, comprising:

a left longitudinal support bar and a right longitudinal support bar which are located on both lateral sides of the bed frame respectively and extend in a longitudinal direction of the bed frame;

an intermediate longitudinal support bar disposed between the left longitudinal support bar and the right longitudinal support bar and extending in the longitudinal direction of the bed frame,

four sliding sleeves, wherein two sliding sleeves are disposed spaced apart on the left longitudinal support bar and capable of sliding on the left longitudinal support bar, and the remaining two sliding sleeves are disposed spaced apart on the right longitudinal support bar and capable of sliding on the right longitudinal support bar, wherein a bracket is disposed on the sliding sleeve; and

four connecting rods comprising two left connecting rods extending between the left longitudinal support bar and

11

the intermediate longitudinal support bar and two right connecting rods extending between the right longitudinal support bar and the intermediate longitudinal support bar, wherein one end of each of the connecting rods is pivotally attached to an end of the intermediate longitudinal support bar about a pivot shaft, and the other end of the connecting rod is pivotally attached to the corresponding bracket, wherein the connecting rod is configured in a way that the end of the connecting rod mounted on the bracket moves along with the sliding sleeve when the sliding sleeve slides along the left longitudinal support bar or right longitudinal support bar, thereby driving the connecting rod to move on a horizontal plane such that the bed frame is in an unfolded state or a folded state; and wherein the bed frame further comprises at least two additional links extending between the left longitudinal support bar and the connecting rods or between the right longitudinal support bar and the connecting rods, one end of each of the additional links is pivotally connected to one end of the left longitudinal support bar or the right longitudinal support bar, the other end is pivotally connected to the connecting rod, and when the connecting rod moves in a horizontal plane, the additional link can be driven by the connecting rod to move in a horizontal plane.

According to a further embodiment of the invention, the additional links comprise two additional links, and the two additional links are located on the same side relative to the intermediate longitudinal support bar; or

the additional links comprise two additional links, and the two additional links are located on different sides relative to the intermediate longitudinal support bar.

According to a further embodiment of the invention, the additional links comprise two additional links, and the two additional links are located on different sides relative to the intermediate longitudinal support bar, and one ends of the two additional links are respectively connected to opposing ends of the intermediate longitudinal support bar.

According to a further embodiment of the invention, the additional links comprise four additional links

According to a further embodiment of the invention, when the sliding sleeves slide toward each other along the left longitudinal support bar or right longitudinal support bar, the bed frame is gradually folded until the bed frame gets into the folded state in which the left longitudinal support bar, the right longitudinal support bar, the intermediate longitudinal support bar and the connecting rods abut against one another; when the sliding sleeves slide away from each other along the left longitudinal support bar or right longitudinal support bar, the bed frame is gradually unfolded until the bed frame gets into a state in which the respective connecting rods are perpendicular to the left longitudinal support bar, the right longitudinal support bar and the intermediate longitudinal support bar, respectively.

According to a further embodiment of the invention, the left longitudinal support bar or right longitudinal support bar is provided with a pin hole at positions close to its end portions and middle portion respectively and at a transition position between the end portions and the middle portion, respectively, a pin is disposed in the pin hole, and the pin is configured to extend out of the pin hole under the action of an elastic force and retract back into the pin hole when subjected to pressure.

According to a further embodiment of the invention, a receiving hole is disposed on a side of the sliding sleeve opposite to the pin hole, wherein the receiving hole is

12

configured in a way that when the receiving hole is aligned with the pin, the pin can extend out under the action of its elasticity, and automatically enter the receiving hole to lock the sliding sleeve on the left longitudinal support bar or right longitudinal support bar.

According to a further embodiment of the invention, the pin holes at the end portions of the left longitudinal support bar or right longitudinal support bar are positioned in a way that the connecting rods are perpendicular to the intermediate longitudinal support bar when the connecting rods are locked on the left longitudinal support bar or right longitudinal support bar; the pin hole at the middle portion of left longitudinal support bar or right longitudinal support bar is positioned in a way that when the connecting rods are locked, the connecting rods and the intermediate longitudinal support bar abut against one another side by side; the pin hole at the transition position of left longitudinal support bar or right longitudinal support bar is positioned in a way that when the connecting rods are locked, an angle between the connecting rods and the intermediate longitudinal support bar is an acute angle.

According to a further embodiment of the invention, the pin is a square pin or a round pin.

According to a further embodiment of the invention, the pin holes are provided on an upper surface and/or a lower surface of the left longitudinal support bar or the right longitudinal support bar.

According to a further embodiment of the invention, the bracket is mounted on the sliding sleeve, and the bracket is provided with a pivot shaft located on both lateral sides of the sliding sleeve and extending in a vertical direction, and the connecting rod is pivotally connected to the bracket via the pivot shaft.

According to a further embodiment of the invention, the bracket comprises an upper plate mounted on an upwardly facing surface of the sliding sleeve and a lower plate fixedly mounted on a downwardly facing surface of the sliding sleeve, both lateral sides of the upper plate and lower plate respectively extend out of the sliding sleeve to form cantilevers, and the pivot shafts are connected between the cantilevers on the same side of the upper plate and lower plate.

According to a further embodiment of the invention, the upper plate comprises two horizontal engagement plates which are respectively connected to two pivot shafts located on both lateral sides of the sliding sleeve, the engagement plates are in a sector shape and provided with a gear structure on an arcuate edge thereof, the gear structures of the two upper plates connected to one sliding sleeve face each other and can mesh with each other, thereby enabling synchronous rotation of the two connecting rods connected to the sliding sleeve.

According to a further embodiment of the invention, an end of the connecting rod connected to the sliding sleeve has an upper side plate and a lower side plate which extend in the horizontal direction and face each other, and the pivot shaft is located between the upper side plate and the lower side plate, and

the bracket includes a bearing frame and a retaining plate, the bearing frame is fixedly mounted on a lower side of the sliding sleeve and extending laterally relative to the sliding sleeve to be supported below the lower side plate, and the retaining plate is positioned above the lower side plate to achieve limitation of the end of the connecting rod connected to the sliding sleeve in the vertical direction.

According to a further embodiment of the invention, the upper side plate is formed as a partially circular shape, an

13

edge of the circular shape is formed as a gear structure, a rack extending in the longitudinal direction is disposed on both lateral upper edges of the sliding sleeve respectively, the gear structures of two connecting rods connected to one sliding sleeve can respectively mesh with respective racks so that the two connecting rods connected to the sliding sleeve can rotate synchronously.

According to a further embodiment of the invention, the left longitudinal support bar, the right longitudinal support bar and the intermediate longitudinal support bar respectively comprise two main body sections and an intermediate section connected between the two main body sections, the main body sections and the intermediate section are connected via a connecting sheet, a support bar pivot shaft is mounted on the connecting sheet, the two main body sections are configured to be capable of rotating relative to each other about their respective support bar pivot shafts in a vertical plane relative to the intermediate section so that the bed frame is folded or unfolded in the vertical plane.

According to a further embodiment of the invention, the bed frame further comprises a locking mechanism for locking the main body sections relative to the intermediate section when the main body sections rotate to the folded or unfolded position in the vertical plane.

According to a further embodiment of the invention, the connecting rod comprises a plurality of bushings which are nested one inside another so that the connecting rod is telescopic in its extension direction.

According to a further embodiment of the invention, in any two adjacent bushings, one bushing is provided with a first alignment hole, a ball end leaf spring with a protrusion is disposed in the first alignment hole, the ball end leaf spring is configured to extend out of the first alignment hole under action of an elastic force and retract back into the first alignment hole when subjected to a pressure, the other the bushing is nested around a preceding bushing, a second alignment hole is disposed on a side face of the other bushing opposite to the first alignment hole, the second alignment hole is configured in a way that when the second alignment hole aligns with the protrusion, the protrusion can extend out under the action of elasticity, automatically enter the second alignment hole and thereby lock the two adjacent bushings relative to one another.

According to a further embodiment of the invention, the bed frame is configured to be engageable with a tongue member for mounting a headboard, the tongue member comprises a tongue, an upwardly open slot is provided at the end of the left longitudinal support bar and right longitudinal support bar, and the slot is configured to receive the tongue.

According to a further embodiment of the invention, the left longitudinal support bar, the right longitudinal support bar, and the intermediate longitudinal support bar are respectively provided with downwardly extending legs at both ends and in the middle.

In one embodiment, the legs are also pivotally connected to respective longitudinal support bars, the legs are rotatable and foldable relative to the respective longitudinal support bars, and in the folded state the legs abut against the respective longitudinal support bars side by side.

In the bed frame provided by the present disclosure, the longitudinal support bars are set to include a plurality of sections which are pivotally connected. Such arrangement can enable quick and effective folding of the bed frame. The space occupied by the folded bed frame is small. The folding process is relatively simple and easy to implement, and the bed frame can satisfy many demands of the user.

14

In addition, the bed frame of the present disclosure is configured to be detachable, which not only facilitates the manufacturer to transport in a small transportation space, thereby saving transportation costs, but also allows users to easily disassemble and reassemble the bed frame to save storage space.

BRIEF DESCRIPTION OF DRAWINGS

- 10 Reference may be made to preferred embodiments shown in the figures to enable better understanding of the above and other objects, features, advantages and functions of the present disclosure. The same reference numerals in the figures denote the same parts. Those skilled in the art should appreciate that the figures are intended to schematically illustrate the preferred embodiments of the present disclosure, and not intended to impose any limitations to the scope of the present disclosure. All parts in the figures are not drawn to scale.
- 15 FIG. 1 is a schematic view of a bed frame according to a first embodiment of the present disclosure, wherein the bed frame is in a semi-unfolded state;

- 75 FIG. 16 through FIG. 18 are several alternative structures of FIG. 15.

DETAILED DESCRIPTION OF PREFERRED EMBODIMENTS

Specific embodiments of the present disclosure will now be described in detail with reference to the figures. Those skilled in the art can implement other manners of the present disclosure on the basis of the preferred embodiments, and other manners also fall within the scope of the present disclosure.

Referring to FIG. 1 through FIG. 13, a bed frame is provided in a first embodiment of the present disclosure.

Referring to FIG. 1 through FIG. 3, it can be seen that the bed frame includes a left longitudinal support bar 1, a right longitudinal support bar 2 and an intermediate longitudinal support bar 3 therebetween which are highly rigid and used to bear a weight. The three longitudinal support bars each extend in a longitudinal direction, and the three longitudinal support bars are each provided with legs 8 located at both ends and in the middle and extending downward. At the

15

same time, the intermediate longitudinal support bar 3 is provided with two sliding sleeves 4 spaced apart from each other a certain distance and being capable of sliding on the intermediate longitudinal support bar 3, and the sliding sleeves 4 are mounted with brackets.

It should be appreciated that extension directions of the various components mentioned in the present disclosure (for example, "a transverse direction", "a longitudinal direction" and "a vertical direction") all refer to the extensions directions of the components in the case that the bed frame is placed in a horizontal plane, so directional terms mentioned in the text should be understood to be relative terms rather than absolute terms. Furthermore, it can be understood that both "transverse direction" and "longitudinal direction" are horizontal directions, and they together define a horizontal plane, and the vertical direction is a direction perpendicular to the horizontal plane.

Further referring to FIG. 1 through FIG. 3, connecting rods 5 are further connected between the left longitudinal support bar 1 or the right longitudinal support bar 2 and the intermediate longitudinal support bar 3, and there are totally four connecting rods 5.

The bed frame is configured to be foldable in a vertical plane so as to reduce the space occupied in the folded state. Referring to FIG. 8 to FIG. 10, it can be seen that each of the three support bars includes three sections: two main body sections (that is, a first main body section 11 and a second main body section 13) and an intermediate section 12 connected between the two main body sections. A connection sheet 14 is provided at a position where the main body sections are connected to the intermediate section 12.

A first through hole extending and running through transversely is disposed at an end of each of the main body sections adjacent to the intermediate section 12, the connecting sheet 14 is provided with a second through hole on a side connected to the main body section. When the second through hole is aligned with the first through hole, a support bar pivot shaft 15 can run through the first through hole and second through hole so that the two main body sections can rotate relative to each other about their respective support bar pivot shafts 15 in a vertical plane relative to the intermediate section 12, so that the bed frame is folded or unfolded in the vertical plane. FIG. 9 through FIG. 10 show a process in which the bed frame is gradually folded, and the arrows in FIG. 9 show the moving direction of the main body sections.

More preferably, a length of the intermediate section 12 may be set equal to that of the legs 8 (which will be described in detail later), so that the bed frame, after being folded in the vertical surface, may form a relatively standard rectangle in the vertical surface, as shown in FIG. 10. As such, the bed frame can be stored conveniently, occupies a reduced space and is visually beautiful.

Preferably, one end of each connecting rod 5 is pivotally attached to an end of the left longitudinal support bar 1 or right longitudinal support bar 2 about a pivot shaft, and the other end of the connecting rod is pivotally attached to a corresponding bracket about a pivot shaft. As such, when the sliding sleeve 4 slides along the intermediate longitudinal support bar 3, the end of the connecting rod 5 connected to the corresponding bracket moves along with the sliding sleeve 4, thereby driving the connecting rod 5 to move in a horizontal plane and thereby transversely unfolding or folding the bed frame.

Specifically, when the two sliding sleeves 4 slide toward each other along the intermediate longitudinal support bar 3, the bed frame is gradually folded until it gets into a folded

16

state in which the left longitudinal support bar 1, the right longitudinal support bar 2 and the intermediate longitudinal support bar 3 abut against one another side by side, the folded state being shown by FIG. 3; when the sliding sleeves 4 slide away from each other along the intermediate longitudinal support bar 3, the bed frame is gradually unfolded until the bed frame gets into an unfolded state in which the respective connecting rods 5 are perpendicular to respective longitudinal support bars respectively, the unfolded state being shown by FIG. 2.

In order to fix the sliding sleeve 4 on the intermediate longitudinal support bar 3 and thereby fix the connecting rods 5, a pin hole is provided on a surface of the intermediate longitudinal support bar 3, an elastic pin is disposed in the pin hole, the pin hole is configured to extend out of the pin hole under the action of an elastic force and retract back into the pin hole when subjected to a pressure, a surface of the sliding sleeve 4 corresponding to the pin hole is provided with a receiving hole 41, and the pin and the receiving hole 41 can engage with each other to lock the sliding sleeve 4. Specifically, the pin hole includes end pin holes and a middle pin hole which respectively receive end pins and a middle pin, and the end pin holes and the middle pin hole are respectively located at the intermediate longitudinal support bar 3 close to its end positions and close to a middle position.

Wherein, the end pin is used to engage with the receiving hole 41 to fix the connecting rod 5 perpendicular to the longitudinal support bar. When the end pin engages with the receiving hole 41, the connecting rod 5 extends transversely, and the bed frame is in the unfolded state as stated above; the middle pin is used to engage with the receiving hole 41 to fix the connecting rod 5 parallel to the longitudinal support bar, and when the middle pin engages with the receiving hole 41, the bed frame is in the folded state as described above.

Preferably, an intermediate pin hole may be provided at an intermediate position between the end pin hole and the middle pin hole to fix the bed frame in a semi-unfolded state, which may be similar to that shown in FIG. 1. On the intermediate longitudinal support bar 3, a distance between the two middle pin holes may be $\frac{1}{5}$ - $\frac{1}{3}$ of the length of the intermediate longitudinal support bar 3, for example $\frac{1}{4}$. Each of the examples shown in FIGS. 4 to 7 may be understood to mean that the intermediate pin engages with the receiving hole 41 to fix the bed frame in the semi-unfolded state, whereupon an angle between the connecting rods and the intermediate longitudinal support bar is an acute angle so that the bed frame is formed as a twin size bed frame.

More preferably, more pin holes and pins at multiple different positions may be disposed so that the angle between the connecting rods 5 and respective longitudinal support bars gradually changes such that the bed frame can be fixed at different positions to change more sizes. For example, when the bed frame is completely folded in the horizontal plane, it is formed as a single size bed frame; when the bed frame is semi-unfolded in the horizontal plane, it is formed as a twin size bed frame; next, the bed frame may be further unfolded again for many times such that the bed frame is formed as a full size bed frame, a queen size bed frame, a king size bed frame, a California king size bed frame or the like.

Preferably, the pin may be a round pin 61 (as shown in FIGS. 4, 5 and 7) or a square pin 62 (as shown in FIG. 6) which may be disposed on an upper surface and/or lower surface of the intermediate longitudinal support bar 3. More preferably, as shown in FIG. 7, the sliding sleeve 4 may

further be provided with a plurality of receiving holes 41 arranged in the longitudinal direction, and each of the receiving holes 41 can engage with the pin to lock the sliding sleeve 4 to different positions of the intermediate longitudinal support bar 3.

The arrangement of the connection of the connecting rod 5 to the sliding sleeve 4 may have various implementation modes, and several examples are shown in FIG. 4 to FIG. 7. In several modes, the bracket 4 is mounted with a bracket, and the bracket is provided with a pivot shaft 725 positioned on both lateral sides of the sliding sleeve 4 and extending in a vertical direction, and the connecting rod 5 is connected to the bracket via the pivot shaft 725.

In the solution shown in FIG. 4, the bracket includes an upper plate 711 mounted on an upward facing surface of the sliding sleeve 4 and a lower plate 712 fixedly mounted on a downward facing surface of the sliding sleeve 4, both lateral sides of the upper plate 711 and lower plate 712 respectively extend out of the sliding sleeve 4 to form cantilevers, and the pivot shaft 725 is connected between the cantilevers on the same side of the upper plate 711 and lower plate 712.

FIG. 5 and FIG. 6 show variations of the solution shown in FIG. 4. In FIG. 5 and FIG. 6, the upper plate 711 includes two horizontal engagement plates 52 which are respectively connected to two pivot shafts 725 located on both lateral sides of the sliding sleeve 4, and the engagement plates 52 are rotatable relative to the sliding sleeve 4 in a horizontal plane. The engagement plates 52 are in a sector shape and provided with a gear structure 521 on an arcuate edge thereof. The two gear structures 521 connected to one sliding sleeve 4 face each other and can mesh with each other, thereby enabling synchronous rotation of the two connecting rods 5 connected to the sliding sleeve 4 when the sliding sleeve 4 slides. The solutions of FIG. 5 and FIG. 6 are substantially similar, but it can be seen that the locking of the sliding sleeve 4 is achieved via the round pin 61 disposed on the upper surface of the support bar and the receiving hole 41 corresponding thereto in FIG. 5, and the locking of the sliding sleeve 4 is achieved via the square pin 62 disposed on the lower surface of the support bar and the receiving hole corresponding thereto in FIG. 6.

Then turning to FIG. 7, FIG. 7 shows a further variation of FIG. 4. An end of the connecting rod 5 connected to the sliding sleeve 4 has an upper side plate 721 and a lower side plate 723 which extend in the horizontal direction and face each other, and the upper side plate 721 and the lower side plate 723 are connected by a vertical connecting portion 722. The pivot shaft 725 is located between the upper side plate 721 and the lower side plate 723. Furthermore, the bracket includes a bearing frame 715 and a retaining plate 724, the bearing frame 715 is fixedly mounted on the lower side of the sliding sleeve 4 and extending laterally relative to the sliding sleeve 4 to be supported below the lower side plate 723, and the retaining plate 724 is positioned above the lower side plate 723 to achieve limitation of the end of the connecting rod 5 connected to the sliding sleeve 4 in the vertical direction.

Further referring to FIG. 7, the upper side plate 721 is formed as a substantially circular shape, an edge of the circular shape is formed as a gear structure 521, a rack 42 extending in the longitudinal direction is disposed on both lateral upper edges of the sliding sleeve 4 respectively, the gear structures 521 of two connecting rods 5 connected to a sliding sleeve 4 can respectively mesh with respective racks 42 so that the two connecting rods 5 connected to the sliding sleeve 4 can rotate synchronously when the sliding sleeve 4 slides.

On the other hand, in order to further adjust the size of the bed frame in the transverse direction, the connecting rod 5 may be arranged to include at least two bushings which are nested one inside the other so that the connecting rod 5 is telescopic in its extension direction. When the bed frame is already in the unfolded state, the size of the bed frame as a whole in the transverse direction can be further adjusted by adjusting the size of an overlapping portion between adjacent bushings.

For example, in the bed frame of FIG. 11, each of the connecting rods 5 includes two bushings—a first bushing 51 and a second bushing 52, whereas in the bed frame in FIG. 12, each of the connecting rods 5 further comprises a third bushing 53. Preferably, the fixation between adjacent bushings may be achieved by providing a ball end leaf spring 53 between the bushings. For the two adjacent bushings, one bushing is provided with a first alignment hole, and an elastic ball end leaf spring 53 with a protrusion 531 is disposed in the first alignment hole, the ball end leaf spring 53 can allow the protrusion 531 to extend out of the first alignment hole under action of an elastic force, and allow the protrusion 531 to retract when compressed. The other bushing is nested around a preceding bushing, a second alignment hole is disposed on the second bushing, and when the second alignment hole aligns with the first alignment hole, the protrusion 531 extends into the second alignment hole under the action of the elasticity of the ball end leaf spring 53, thereby locking the two bushings.

Preferably, the bed frame is also engageable with a tongue member 9 for mounting a headboard, the tongue member 9 comprises a tongue 91, an upwardly open slot 16 is further provided at the end of the left longitudinal support bar 1 and right longitudinal support bar 2, and the tongue 91 can be inserted into the slot 16.

At the same time, in other embodiments not shown, the bed frame may also have other arrangements. For example, it is also possible to arrange the legs 8 below the longitudinal support bars to be foldable, for example to pivotally connect the legs 8 to the longitudinal support bars, the legs 8 being capable of abutting against the respective longitudinal support bars when the legs 8 are folded.

FIG. 14 shows a second embodiment of the disclosure.

In the present embodiment, two sliding sleeves 4 are disposed spaced apart on both the left longitudinal support bar 1 and right longitudinal support bar 2, and the sliding sleeves 4 are slideable on the longitudinal support bars. Therefore, in the present embodiment, there are a total of four sliding sleeves 4, and the sliding sleeves 4 each are provided with a bracket.

There are still a total of four connecting rods 5, one end of each connecting rod 5 is pivotally attached to the end of the intermediate longitudinal support bar 3 about a pivot shaft, and the other end of the connecting rod 5 is pivotally attached to a corresponding bracket about a pivot shaft.

Wherein, when the sliding sleeve 4 slides along the corresponding longitudinal support bar, one end of the sliding sleeve 4 mounted on the bracket moves along with the sliding sleeve 4, thereby driving the connecting rod 5 to rotate in a horizontal plane, and thereby causing the bed frame to be in an unfolded state or folded state.

Other configurations and arrangements of the present embodiment are similar to those of the previous embodiment, and are not described any longer herein for the sake of simplicity.

FIG. 15 through FIG. 18 show a third embodiment of the present disclosure. The basic structure of the bed frame in the present embodiment is similar to that of the first embodi-

ment described above. In the present embodiment, the bed frame further includes an additional link 56 extending between the intermediate longitudinal support bar 3 and the connecting rod, one end of each additional link 56 is pivotally connected to one end of the intermediate longitudinal support bar 3, and when the connecting rod is driven by the sliding sleeve 4 to move in a horizontal plane, the additional link 56 can be driven by the connecting rod to move in a horizontal plane.

In the solutions shown in FIG. 15 and FIG. 16, there are two additional links 56 which are located on the same side relative to the intermediate longitudinal support bar 3. In FIG. 15, the two additional links 56 are respectively connected to two right connecting rods 55 (i.e., connecting rods between the right longitudinal support bar 2 and the intermediate longitudinal support bar 3); in FIG. 16, the two additional links 56 are respectively connected to two left connecting rods 54 (i.e., connecting rods between the left longitudinal support bar 1 and the intermediate longitudinal support bar 3).

In the solution shown in FIG. 17, there are two additional links 56 which are located on different sides relative to the intermediate longitudinal support bar 3, and the two additional links 56 are respectively connected to the opposed ends of the intermediate longitudinal support bar 3. It can be seen from FIG. 17, the two additional links 56 are located on both lateral sides of the bed frame, one is connected to the left connecting rod 54, and the other is connected to the right connecting rod 55.

In another solution, there may be four additional links 56 which are connected one to one with the four connecting rods. FIG. 18 shows the structure at one transverse end of the bed frame in this solution, and two additional links 56 are connected to the left connecting rod 54 and the right connecting rod 55, respectively. It may be appreciated that the structure at the other transverse end of the bed frame is substantially similar to the structure shown in FIG. 18.

In other embodiments not shown, it is also possible to additionally provide additional links on the basis of the bed frame of the second embodiment. Specifically, the bed frame may further comprise at least two additional links extending between the left longitudinal support bar and the connecting rod or between the right longitudinal support bar and the connecting rod, one end of each additional link is pivotally attached to one end of the left longitudinal support bar or right longitudinal support bar, the other end is pivotally connected to the connecting rod, and, the additional links can be driven to move in the horizontal plane when the connecting rod moves in the horizontal plane.

The additional links may also be arranged in many ways. For example, the additional links may comprise two additional links, and the two additional links are located on the same side relative to the intermediate longitudinal support bar; or the two additional links are located on different sides relative to the intermediate longitudinal support bar.

Preferably, the two additional links are located on different sides relative to the intermediate longitudinal support bar, and one end of each of the two additional links is connected to an opposed end of the intermediate longitudinal support bar.

Or, there are four additional links which may be connected one to one with the four connecting rods.

The provision of the additional links can reinforce the strength of the bed frame; especially when the bed frame is in a semi-unfolded state, the additional links can function to assist in supporting. Moreover, the provision of the additional links can also enable more firm and stable connection

between the intermediate longitudinal support bar and the left longitudinal support bar and the right longitudinal support bar.

In the bed frame provided by the present disclosure, the support bars for bearing weight are connected via the connecting rods, the connecting rods are driven to move by enabling an end of the connecting rods to slide on the support bars, thereby achieving the unfolding or folding of the bed frame. Such arrangement can enable quick and effective folding of the bed frame. The space occupied by the folded bed frame is small. The folding process is relatively simple and easy to implement. Furthermore, the bed frame exhibits better strength and stability. In either the unfolded state or folded state, the bed frame can bear a larger weight and can satisfy many demands of the user.

Additional Embodiments

The following are additional embodiments, beginning with embodiment 21 as listed below:

21. A bed frame, comprising:
a left longitudinal support bar and a right longitudinal support bar which are located at a left side and a right side of the bed frame respectively and extend in a longitudinal direction of the bed frame;
an intermediate longitudinal support bar disposed between the left longitudinal support bar and the right

21

longitudinal support bar and extending in the longitudinal direction of the bed frame, wherein the left longitudinal support bar, the right longitudinal support bar and the intermediate longitudinal support bar respectively comprise two main body sections and an intermediate section connected between the two main body sections, the main body sections and the intermediate section are connected via a connecting sheet,

wherein a first through hole extending and running through transversely is disposed at an end of each of the main body sections adjacent to the intermediate section, the connecting sheet is provided with a second through hole on a side connected to the main body section; when the second through hole is aligned with the first through hole, a support bar pivot shaft can run through the first through hole and second through hole so that the two main body sections can rotate about their respective support bar pivot shafts in a vertical plane relative to the intermediate section, so that the bed frame is folded or unfolded in the vertical plane; the bed frame comprising:

four sliding sleeves, wherein two sliding sleeves are disposed spaced apart on the left longitudinal support bar and capable of sliding on the left longitudinal support bar, and the other two sliding sleeves are disposed spaced apart on the right longitudinal support bar and capable of sliding on the right longitudinal support bar, wherein a bracket is disposed on the sliding sleeve; and

four connecting rods comprising two left connecting rods extending between the left longitudinal support bar and the intermediate longitudinal support bar and two right connecting rods extending between the right longitudinal support bar and the intermediate longitudinal support bar, wherein one end of each of the connecting rods is pivotally attached to an end of the intermediate longitudinal support bar about a pivot shaft, and the other end of the connecting rod is pivotally attached to the corresponding bracket;

wherein the connecting rod is configured in a way that the end of the connecting rod mounted on the bracket moves along with the sliding sleeve when the sliding sleeve slides along the left longitudinal support bar or right longitudinal support bar, thereby driving the connecting rod to move on a horizontal plane such that the bed frame is in an unfolded state or a folded state.

wherein when the sliding sleeves slide toward each other along the left longitudinal support bar or right longitudinal support bar, the bed frame is gradually folded until the bed frame gets into the folded state in which the left longitudinal support bar, the right longitudinal support bar, the intermediate longitudinal support bar and the connecting rods abut against one another; when the sliding sleeves slide away from each other along the left longitudinal support bar or right longitudinal support bar, the bed frame is gradually unfolded until the bed frame gets into a state in which the respective connecting rods are perpendicular to the left longitudinal support bar, the right longitudinal support bar and the intermediate longitudinal support bar, respectively.

22. The bed frame according to claim 21, wherein a pin hole is disposed on the left longitudinal support bar or right longitudinal support bar at positions close to its end portions and middle portion, respectively, a pin is disposed in the pin hole, and the pin is configured to extend out of the pin holes

22

under the action of an elastic force and retract back into the pin holes when subjected to pressure.

23. The bed frame according to claim 22, wherein a pin hole is also disposed on a middle position between the end portions and the middle portion, a pin is disposed in the pin hole, and the pin is configured to extend out of the pin holes under the action of an elastic force and retract back into the pin holes when subjected to pressure.

24. The bed frame according to claim 23, wherein a 10 receiving hole is disposed on a side of the sliding sleeve facing the pin hole, wherein the receiving hole is configured in a way that when the receiving hole is aligned with the pin, the pin can extend out under the action of its elasticity, and automatically enter the receiving hole to lock the sliding 15 sleeve on the corresponding left longitudinal support bar or right longitudinal support bar.

25. The bed frame according to claim 24, wherein the pin holes at the end portions of the left longitudinal support bar or right longitudinal support bar are positioned in a way that 20 the connecting rods are perpendicular to the intermediate longitudinal support bar when the connecting rods are locked on the left longitudinal support bar or right longitudinal support bar; the pin hole at the middle portion of left longitudinal support bar or right longitudinal support bar is positioned in a way that when the connecting rods are locked, the connecting rods and the intermediate longitudinal support bar abut against one another side by side; the pin hole at a transition position of left longitudinal support bar or right longitudinal support bar is positioned in a way that 30 when the connecting rods are locked, an angle between the connecting rods and the intermediate longitudinal support bar is an acute angle so that a width of the bed frame is adapted for dimension requirements of a twin size bed.

26. The bed frame according to claim 22, wherein the pin 35 is a square pin or a round pin.

27. The bed frame according to claim 22, wherein the pin holes are provided on an upper surface and/or a lower surface of the left longitudinal support bar or the right longitudinal support bar.

40. 28. The bed frame according to claim 21, wherein the bracket is mounted on the sliding sleeve, and the bracket is provided with a pivot shaft located on both lateral sides of the sliding sleeve and extending in a vertical direction, and the connecting rod is pivotally connected to the bracket via 45 the pivot shaft.

29. The bed frame according to claim 28, wherein the bracket comprises an upper plate mounted on an upwardly facing surface of the sliding sleeve and a lower plate fixedly mounted on a downwardly facing surface of the sliding sleeve, both lateral sides of the upper plate and lower plate 50 respectively extend out of the sliding sleeve to form cantilevers, and the pivot shafts are connected between the cantilevers on the same side of the upper plate and lower plate.

55. 30. The bed frame according to claim 33, wherein the upper plate comprises two horizontal meshing plates which are respectively connected to two pivot shafts located on both lateral sides of the sliding sleeve, the meshing plates are in a sector shape and provided with a gear structure on an arcuate edge thereof, the gear structures of the two upper 60 plates connected to one sliding sleeve face each other and can mesh with each other, thereby enabling synchronous rotation of the two connecting rods connected to the sliding sleeve.

65. 31. The bed frame according to claim 28, wherein an end of the connecting rod connected to the sliding sleeve has an upper side plate and a lower side plate which extend in the

horizontal direction and face each other, and the pivot shaft is located between the upper side plate and the lower side plate, and the bracket includes a bearing frame and a retaining plate, the bearing frame is fixedly mounted on a lower side of the sliding sleeve and extending laterally relative to the sliding sleeve to be supported below the lower side plate, and the retaining plate is positioned above the lower side plate to achieve limitation of the end of the connecting rod connected to the sliding sleeve in the vertical direction.

32. The bed frame according to claim 31, wherein the upper side plate is formed as a partially circular shape, an edge of the circular shape is formed as a gear structure, a rack extending in the longitudinal direction is disposed on both lateral upper edges of the sliding sleeve respectively, the gear structures of two connecting rods connected to one sliding sleeve can respectively mesh with respective racks so that the two connecting rods connected to the sliding sleeve can rotate synchronously.

33. The bed frame according to claim 21, wherein the bed frame is configured to be engageable with a tongue member for mounting a headboard, the tongue member comprises a tongue, an upwardly open slot is provided at the end of the left longitudinal support bar and right longitudinal support bar, and the slot is configured to receive the tongue.

34. The bed frame according to claim 21, wherein the left longitudinal support bar, the right longitudinal support bar, and the intermediate longitudinal support bar are respectively provided with downwardly extending legs at both ends and in the middle.

35. The bed frame according to claim 34, wherein the legs are also pivotally connected to respective longitudinal support bars, the legs are rotatable and foldable relative to the respective longitudinal support bars, and in the folded state the legs abut against the respective longitudinal support bars side by side.

36. A bed frame, comprising:

a left longitudinal support bar and a right longitudinal support bar which are located at a left side and a right side of the bed frame respectively and extend in a longitudinal direction of the bed frame;

an intermediate longitudinal support bar disposed between the left longitudinal support bar and the right longitudinal support bar and extending in the longitudinal direction of the bed frame,

wherein the left longitudinal support bar, the right longitudinal support bar and the intermediate longitudinal support bar respectively comprise two main body sections and an intermediate section connected between the two main body sections, the main body sections and the intermediate section are connected via a connecting sheet,

wherein a first through hole extending and running through transversely is disposed at an end of each of the main body sections adjacent to the intermediate section, the connecting sheet is provided with a second through hole on a side connected to the main body section; when the second through hole is aligned with the first through hole, a support bar pivot shaft can run through the first through hole and second through hole so that the two main body sections can rotate about their respective support bar pivot shafts in a vertical plane relative to the intermediate section, so that the bed frame is folded or unfolded in the vertical plane; wherein the bed frame further comprises:

two spaced-apart sliding sleeves disposed on the intermediate longitudinal support bar and being slidable on the

intermediate longitudinal support bar, wherein a bracket is disposed on the sliding sleeve; and four connecting rods comprising two left connecting rods extending between the left longitudinal support bar and the intermediate longitudinal support bar and two right connecting rods extending between the right longitudinal support bar and the intermediate longitudinal support bar, wherein one end of each of the connecting rods is pivotally attached to an end of the left longitudinal support bar or the right longitudinal support bar, and the other end of the connecting rod is pivotally attached to the corresponding bracket,

wherein the connecting rod is configured in a way that the end of the connecting rod mounted on the bracket moves along with the sliding sleeve when the sliding sleeve slides along the intermediate longitudinal support bar, thereby driving the connecting rod to move on a horizontal plane such that the bed frame is in an unfolded state or a folded state; and

wherein the bed frame further comprises at least two additional links extending between the intermediate longitudinal support bar and the connecting rods, one end of each of the additional links is pivotally connected to one end of the intermediate longitudinal support bar, the other end is pivotally connected to the connecting rod, and when the connecting rod moves in a horizontal plane, the additional link can be driven by the connecting rod to move in a horizontal plane.

37. The bed frame according to claim 36 wherein the additional links comprise two additional links, and the two additional links are located on the same side relative to the intermediate longitudinal support bar; or the additional links comprise two additional links, and the two additional links are located on different sides relative to the intermediate longitudinal support bar.

38. The bed frame according to claim 36 wherein the additional links comprise two additional links, and the two additional links are located on different sides relative to the intermediate longitudinal support bar, and one ends of the two additional links are respectively connected to opposing ends of the intermediate longitudinal support bar.

39. The bed frame according to claim 36 wherein the additional links comprise four additional links

40. The bed frame according to claim 36 wherein when the sliding sleeves slide toward each other along the intermediate longitudinal support bar, the bed frame is gradually folded until the bed frame gets into the folded state in which the left longitudinal support bar, the right longitudinal support bar, the intermediate longitudinal support bar and the connecting rods abut against one another; when the sliding sleeves slide away from each other along the intermediate longitudinal support bar, the bed frame is gradually unfolded until the bed frame gets into a state in which the respective connecting rods are perpendicular to the left longitudinal support bar, the right longitudinal support bar and the intermediate longitudinal support bar, respectively.

41. The bed frame according to claim 36, wherein the intermediate longitudinal support bar is provided with a pin hole at positions close to its end portions and middle portion respectively, a pin is disposed in the pin hole, and the pin is configured to extend out of the pin hole under the action of an elastic force and retract back into the pin hole when subjected to pressure.

42. The bed frame according to claim 39, wherein a pin hole is also disposed on a middle position between the end portions and the middle portion, a pin is disposed in the pin hole, and the pin is configured to extend out of the pin holes

under the action of an elastic force and retract back into the pin holes when subjected to pressure.

43. The bed frame according to claim 40, wherein a receiving hole is disposed on a side of the sliding sleeve facing the pin hole, wherein the receiving hole is configured in a way that when the receiving hole is aligned with the pin, the pin can extend out under the action of its elasticity, and automatically enter the receiving hole to lock the sliding sleeve on the intermediate longitudinal support bar.

44. The bed frame according to claim 41, wherein the pin holes at the end portions of the intermediate longitudinal support bar are positioned in a way that the connecting rods are perpendicular to the intermediate longitudinal support bar when the connecting rods are locked on the intermediate longitudinal support bar; the pin hole at the middle portion of the intermediate longitudinal support bar is positioned in a way that when the connecting rods are locked, the connecting rods and the intermediate longitudinal support bar abut against one another side by side; the pin hole at the middle position of the intermediate longitudinal support rod is positioned in a way that when the connecting rods are locked, an angle between the connecting rods and the intermediate longitudinal support bar is an acute angle so that a width of the bed frame is adapted for dimension requirements of a twin size bed.

45. The bed frame according to claim 41, wherein the pin is a square pin or a round pin.

46. The bed frame according to claim 41, wherein the pin holes are provided on an upper surface and/or a lower surface of the intermediate longitudinal support bar.

47. The bed frame according to claim 36, wherein the bracket is mounted on the sliding sleeve, and the bracket is provided with a pivot shaft located on both lateral sides of the sliding sleeve and extending in a vertical direction, and the connecting rod is pivotally connected to the bracket via the pivot shaft.

48. The bed frame according to claim 45, wherein the bracket comprises an upper plate mounted on an upwardly facing surface of the sliding sleeve and a lower plate fixedly mounted on a downwardly facing surface of the sliding sleeve, both lateral sides of the upper plate and lower plate respectively extend out of the sliding sleeve to form cantilevers, and the pivot shafts are connected between the cantilevers on the same side of the upper plate and lower plate.

49. The bed frame according to claim 46, wherein the upper plate comprises two horizontal meshing plates which are respectively connected to two pivot shafts located on both lateral sides of the sliding sleeve, the meshing plates are in a sector shape and provided with a gear structure on an arcuate edge thereof, the gear structures of the two upper plates connected to one sliding sleeve face each other and can mesh with each other, thereby enabling synchronous rotation of the two connecting rods.

50. The bed frame according to claim 47, wherein an end of the connecting rod connected to the sliding sleeve has an upper side plate and a lower side plate which extend in the horizontal direction and face each other, and the pivot shaft is located between the upper side plate and the lower side plate, and

the bracket includes a bearing frame and a retaining plate, the bearing frame is fixedly mounted on a lower side of the sliding sleeve and extending laterally relative to the sliding sleeve to be supported below the lower side plate, and the retaining plate is positioned above the

lower side plate to achieve limitation of the end of the connecting rod connected to the sliding sleeve in the vertical direction.

51. The bed frame according to claim 48, wherein the upper side plate is formed as a partially circular shape, an edge of the circular shape is formed as a gear structure, a rack extending in the longitudinal direction is disposed on both lateral upper edges of the sliding sleeve respectively, the gear structures of two connecting rods connected to one sliding sleeve can respectively mesh with respective racks so that the two connecting rods connected to the sliding sleeve can rotate synchronously.

52. The bed frame according to claim 36, wherein the bed frame is configured to be engageable with a tongue member for mounting a headboard, the tongue member comprises a tongue, an upwardly open slot is provided at the end of the left longitudinal support bar and right longitudinal support bar, and the slot is configured to receive the tongue.

53. The bed frame according to claim 36, wherein the left longitudinal support bar, the right longitudinal support bar, and the intermediate longitudinal support bar are respectively provided with downwardly extending legs at both ends and in the middle.

54. The bed frame according to claim 53, wherein the legs are also pivotally connected to respective longitudinal support bars, the legs are rotatable and foldable relative to the respective longitudinal support bars, and in the folded state the legs abut against the respective longitudinal support bars side by side.

55. A bed frame, comprising:
a left longitudinal support bar and a right longitudinal support bar which are located at a left side and a right side of the bed frame respectively and extend in a longitudinal direction of the bed frame;

an intermediate longitudinal support bar disposed between the left longitudinal support bar and the right longitudinal support bar and extending in the longitudinal direction of the bed frame,
wherein the left longitudinal support bar, the right longitudinal support bar and the intermediate longitudinal support bar respectively comprise two main body sections and an intermediate section connected between the two main body sections, the main body sections and the intermediate section are connected via a connecting sheet,

wherein a first through hole extending and running through transversely is disposed at an end of each of the main body sections adjacent to the intermediate section, the connecting sheet is provided with a second through hole on a side connected to the main body section; when the second through hole is aligned with the first through hole, a support bar pivot shaft can run through the first through hole and second through hole so that the two main body sections can rotate about their respective support bar pivot shafts in a vertical plane relative to the intermediate section, so that the bed frame is folded or unfolded in the vertical plane.
wherein the bed frame further comprises:

four sliding sleeves, wherein two sliding sleeves are disposed spaced apart on the left longitudinal support bar and capable of sliding on the left longitudinal support bar, and the other two sliding sleeves are disposed spaced apart on the right longitudinal support bar and capable of sliding on the right longitudinal support bar, wherein a bracket is disposed on the sliding sleeve; and

four connecting rods comprising two left connecting rods extending between the left longitudinal support bar and the intermediate longitudinal support bar and two right connecting rods extending between the right longitudinal support bar and the intermediate longitudinal support bar, wherein one end of each of the connecting rods is pivotally attached to an end of the intermediate longitudinal support bar about a pivot shaft, and the other end of the connecting rod is pivotally attached to the corresponding bracket,

wherein the connecting rod is configured in a way that the end of the connecting rod mounted on the bracket moves along with the sliding sleeve when the sliding sleeve slides along the left longitudinal support bar or right longitudinal support bar, thereby driving the connecting rod to move on a horizontal plane such that the bed frame is in an unfolded state or a folded state; and wherein the bed frame further comprises at least two additional links extending between the left longitudinal support bar and the connecting rods or between the right longitudinal support bar and the connecting rods, one end of each of the additional links is pivotally connected to one end of the left longitudinal support bar or the right longitudinal support bar, the other end is pivotally connected to the connecting rod, and when the connecting rod moves in a horizontal plane, the additional link can be driven by the connecting rod to move in a horizontal plane.

56. The bed frame according to claim 55, wherein the additional links comprise two additional links, and the two additional links are located on the same side relative to the intermediate longitudinal support bar; or the additional links comprise two additional links, and the two additional links are located on different sides relative to the intermediate longitudinal support bar.

57. The bed frame according to claim 56, wherein the additional links comprise two additional links, and the two additional links are located on different sides relative to the intermediate longitudinal support bar, and one ends of the two additional links are respectively connected to opposing ends of the intermediate longitudinal support bar.

58. The bed frame according to claim 55, wherein the additional links comprise four additional links.

59. The bed frame according to claim 55, wherein when the sliding sleeves slide toward each other along the left longitudinal support bar or right longitudinal support bar, the bed frame is gradually folded until the bed frame gets into the folded state in which the left longitudinal support bar, the right longitudinal support bar, the intermediate longitudinal support bar and the connecting rods abut against one another; when the sliding sleeves slide away from each other along the left longitudinal support bar or right longitudinal support bar, the bed frame is gradually unfolded until the bed frame gets into a state in which the respective connecting rods are perpendicular to the left longitudinal support bar, the right longitudinal support bar and the intermediate longitudinal support bar, respectively.

60. The bed frame according to claim 55, wherein the left longitudinal support bar or right longitudinal support bar is provided with a pin hole at positions close to its end portions and middle portion respectively and at a transition position between the end portions and the middle portion, respectively, a pin is disposed in the pin hole, and the pin is configured to extend out of the pin hole under the action of an elastic force and retract back into the pin hole when subjected to pressure.

61. The bed frame according to claim 60, wherein a pin hole is also disposed on a middle position between the end portions and the middle portion, a pin is disposed in the pin hole, and the pin is configured to extend out of the pin holes under the action of an elastic force and retract back into the pin holes when subjected to pressure.

62. The bed frame according to claim 61, wherein a receiving hole is disposed on a side of the sliding sleeve facing the pin hole, wherein the receiving hole is configured in a way that when the receiving hole is aligned with the pin, the pin can extend out under the action of its elasticity, and automatically enter the receiving hole to lock the sliding sleeve on the left longitudinal support bar or right longitudinal support bar.

63. The bed frame according to claim 62, wherein the pin holes at the end portions of the left longitudinal support bar or right longitudinal support bar are positioned in a way that the connecting rods are perpendicular to the intermediate longitudinal support bar when the connecting rods are locked on the left longitudinal support bar or right longitudinal support bar; the pin hole at the middle portion of left longitudinal support bar or right longitudinal support bar is positioned in a way that when the connecting rods are locked, the connecting rods and the intermediate longitudinal support bar abut against one another side by side; the pin hole at a transition position of left longitudinal support bar or right longitudinal support bar is positioned in a way that when the connecting rods are locked, an angle between the connecting rods and the intermediate longitudinal support bar is an acute angle so that a width of the bed frame is adapted for dimension requirements of a twin size bed.

64. The bed frame according to claim 60, wherein the pin is a square pin or a round pin.

65. The bed frame according to claim 60, wherein the pin holes are provided on an upper surface and/or a lower surface of the left longitudinal support bar or the right longitudinal support bar.

66. The bed frame according to claim 55, wherein the bracket is mounted on the sliding sleeve, and the bracket is provided with a pivot shaft located on both lateral sides of the sliding sleeve and extending in a vertical direction, and the connecting rod is pivotally connected to the bracket via the pivot shaft.

67. The bed frame according to claim 66, wherein the bracket comprises an upper plate mounted on an upwardly facing surface of the sliding sleeve and a lower plate fixedly mounted on a downwardly facing surface of the sliding sleeve, both lateral sides of the upper plate and lower plate respectively extend out of the sliding sleeve to form cantilevers, and the pivot shafts are connected between the cantilevers on the same side of the upper plate and lower plate.

68. The bed frame according to claim 67, wherein the upper plate comprises two horizontal meshing plates which are respectively connected to two pivot shafts located on both lateral sides of the sliding sleeve, the meshing plates are in a sector shape and provided with a gear structure on an arcuate edge thereof, the gear structures of the two upper plates connected to one sliding sleeve face each other and can mesh with each other, thereby enabling synchronous rotation of the two connecting rods connected to the sliding sleeve.

69. The bed frame according to claim 66, wherein an end of the connecting rod connected to the sliding sleeve has an upper side plate and a lower side plate which extend in the

horizontal direction and face each other, and the pivot shaft is located between the upper side plate and the lower side plate, and

the bracket includes a bearing frame and a retaining plate, the bearing frame is fixedly mounted on a lower side of the sliding sleeve and extending laterally relative to the sliding sleeve to be supported below the lower side plate, and the retaining plate is positioned above the lower side plate to achieve limitation of the end of the connecting rod connected to the sliding sleeve in the vertical direction.

70. The bed frame according to claim 69, wherein the upper side plate is formed as a partially circular shape, an edge of the circular shape is formed as a gear structure, a rack extending in the longitudinal direction is disposed on both lateral upper edges of the sliding sleeve respectively, the gear structures of two connecting rods connected to one sliding sleeve can respectively mesh with respective racks so that the two connecting rods connected to the sliding sleeve can rotate synchronously.

71. The bed frame according to claim 55, wherein the bed frame is configured to be engageable with a tongue member for mounting a headboard, the tongue member comprises a tongue, an upwardly open slot is provided at the end of the left longitudinal support bar and right longitudinal support bar, and the slot is configured to receive the tongue.

72. The bed frame according to claim 55, wherein the left longitudinal support bar, the right longitudinal support bar, and the intermediate longitudinal support bar are respectively provided with downwardly extending legs at both ends and in the middle.

73. The bed frame according to claim 72, wherein the legs are also pivotally connected to respective longitudinal support bars, the legs are rotatable and foldable relative to the respective longitudinal support bars, and in the folded state the legs abut against the respective longitudinal support bars side by side.

The above depictions of various embodiments of the present disclosure are provided to those having ordinary skill in the art for depiction purpose, and are not intended to exclude other embodiments from the present disclosure or limit the present disclosure to a single disclosed embodiment. As described above, various alternatives and modifications of the present disclosure will be apparent to those of ordinary skill in the art. Accordingly, although some alternative embodiments have been described in detail, those having ordinary skill in the art will understand or readily develop other embodiments. The disclosure is intended to cover all alternatives, modifications and variations of the present disclosure described herein, as well as other embodiments falling within the spirit and scope of the present disclosure described herein.

What is claimed is:

1. A bed frame, comprising:

a left longitudinal support bar and a right longitudinal support bar which extend in a longitudinal direction of the bed frame;

an intermediate longitudinal support bar between the left longitudinal support bar and the right longitudinal support bar and extending in the longitudinal direction of the bed frame;

wherein the left longitudinal support bar, the right longitudinal support bar and the intermediate longitudinal support bar each have two main body sections and an intermediate section connected between the two main body sections, the main body sections and the intermediate section connected via a connecting piece;

the two main body sections rotatable in a vertical plane relative to the intermediate section, to allow the bed frame to be folded or unfolded in the vertical plane; two spaced-apart sliding sleeves slidable on the intermediate longitudinal support bar;

a bracket on each sliding sleeve; two left connecting rods extending between the left longitudinal support bar and the intermediate longitudinal support bar and two right connecting rods extending between the right longitudinal support bar and the intermediate longitudinal support bar, one end of each connecting rod pivotally attached to an end of the left or right longitudinal support bar, and the other end of each connecting rod pivotally attached to one of the brackets;

wherein the end of the connecting rod connected to the bracket moves with the sliding sleeve when the sliding sleeve slides along the intermediate longitudinal support bar, with the connecting rod moving in a horizontal plane as the bed frame is folded and unfolded;

the sliding sleeves slidable toward each other along the intermediate longitudinal support bar until the bed frame is in a folded state, wherein, in the folded state the left longitudinal support bar, the right longitudinal support bar, the intermediate longitudinal support bar and the connecting rods abut against one another, the sliding sleeves slidable away from each other along the intermediate longitudinal support bar as the bed frame is unfolded until the connecting rods are perpendicular to the left longitudinal support bar, the right longitudinal support bar and the intermediate longitudinal support bar;

an end pin hole in first and second end portions of the intermediate longitudinal support bar, and a middle pin hole in a middle portion of the intermediate longitudinal support bar, a pin in each of the end and middle pin holes, the pin configured to extend out of the pin hole under spring force and retract back into the pin hole when pressed;

wherein when a receiving hole in the sliding sleeve is aligned with the pin, the pin can extend out by spring force, and automatically enter the receiving hole to lock the sliding sleeve on the intermediate longitudinal support bar; and

the connecting rods perpendicular to the intermediate longitudinal support bar when the pin is in the end pin holes; and the connecting rods and the intermediate longitudinal support bar abutting against one another when the pin is in the middle pin hole.

2. The bed frame of claim 1 wherein each connecting rod comprises a telescoping connecting rod including a first tube telescopically extendable from a second tube.

3. The bed frame of claim 2 further including an alignment hole in the first tube and a ball end leaf spring with a protrusion on the second tube, the protrusion movable into the alignment hole via spring force to lock the first tube against telescopic movement relative to the second tube.

4. The bed frame of claim 1 wherein the pin is square or round.

5. The bed frame according to claim 4, wherein the pin holes are provided on an upper surface and/or a lower surface of the intermediate longitudinal support bar.

6. The bed frame according to claim 1, wherein the bed frame is configured to be engageable with a tongue member for mounting a headboard, the tongue member comprises a tongue, an upwardly open slot is provided at the end of the

31

left longitudinal support bar and right longitudinal support bar, and the slot is configured to receive the tongue.

7. The bed frame according to claim 1, wherein the left longitudinal support bar, the right longitudinal support bar, and the intermediate longitudinal support bar are respectively provided with downwardly extending legs at both ends and in the middle.

8. The bed frame of claim 7 wherein each leg is pivotally connected to one of the longitudinal support bars, and each leg is rotatable into a folded position wherein the leg abuts against the longitudinal support bar.

9. A bed frame, comprising:

a left longitudinal support bar and a right longitudinal support bar;

an intermediate longitudinal support bar between the left longitudinal support bar and the right longitudinal support bar;

the left, intermediate and right longitudinal support bars each having two main body sections and an intermediate section connected between the two main body sections via a connecting piece;

a support bar pivot shaft extending through holes at an inner end of each main body section and through holes in each connecting piece, so that each main body section can rotate in a vertical plane relative to the intermediate section, to allow the bed frame to be folded or unfolded in the vertical plane;

first and second sleeves slidable on the intermediate longitudinal support bar;

a bracket on each sleeve, each bracket including an upper plate on an upwardly facing surface of the sleeve and a lower plate on a downwardly facing surface of the sleeve, the upper and lower plates each extending out from the sleeve to form left and right cantilevers;

first and second left connecting rods extending between the left longitudinal support bar and the intermediate longitudinal support bar, and first and second right connecting rods extending between the right longitudinal support bar and the intermediate longitudinal support bar;

an outer end of the first and second left connecting rods pivotally attached to an outer end of the left longitudinal support bar about first and second left pivot shafts, an inner end of the first and second left connecting rods pivotally attached to the bracket on the first and second sleeves by first and second left vertical sleeve pivot shafts extending through the left cantilevers on a left side of the first and second sleeves, respectively; and

an outer end of the first and second right connecting rods pivotally attached to an outer end of the right longitudinal support bar about first and second right pivot shafts, an inner end of the first and second right connecting rods pivotally attached to the bracket on the first and second sleeves by first and second right vertical sleeve pivot shafts extending through the right cantilevers on a right side of the first and second sleeves, wherein when the sleeves slide along the intermediate longitudinal support bar, the connecting rods move in a horizontal plane such that the bed frame

50
55
60

32

10. The bed frame of claim 9 wherein the upper plate comprises left and right horizontal engagement plates respectively connected to the left and right sleeve pivot shafts, each engagement plate having a sector shape and a gear structure on an arcuate edge thereof, the gear structures meshing with each other, thereby enabling synchronous movement of the first left and right connecting rods and second left and right connecting rods.

11. The bed frame of claim 9 wherein the inner end of each connecting rod has a horizontal upper side plate and a horizontal lower side plate and the first and second left and right pivot shafts extend between the upper side plate and the lower side plate; and

15 at least one of the brackets includes a bearing frame and a retaining plate, the bearing frame fixed on a lower side of the sleeve below the lower side plate, and the retaining plate positioned above the lower side plate, to limit vertical movement of the inner end of the connecting rod.
